UNITED STATES PATENT OFFICE.

ROBERT C. MITCHELL, OF MOUNT VERNON, NEW YORK.

LIQUID-FUEL-FEEDING APPARATUS.

1,264,958.

Specification of Letters Patent. Patented May 7, 1918.

Application filed June 3, 1916. Serial No. 101,514.

To all whom it may concern:

Be it known that I, ROBERT C. MITCHELL, a citizen of the United States of America, residing at Mount Vernon, Westchester county, New York State, have invented a new and useful Liquid-Fuel-Feeding Apparatus, (XX,) of which the following is a specification.

My invention relates to certain new and useful improvements in liquid fuel feed tanks, which may be used to advantage in connection with feeding fuel to an engine vaporizer or carburetor. I provide mechanism whereby said feed tank may be filled from a supply tank arranged at a lower level, said filling process being effected by creating a partial vacuum in the feed tank when desired to restore and maintain the level of the fluid therein substantially constant.

In the drawings:

Figure 1 is a vertical sectional view showing certain parts in elevation.

Fig. 2 is a perspective view of a detail relatively enlarged.

Fig. 3 is a view similar to Fig. 1, but illustrating a modification.

T represents a main fuel supply tank. C represents a vaporizer or carburetor. E represents any suitable means for creating exhaust, for example, it may represent part of the intake pipe or so-called manifold of an internal combustion engine. 1 represents the fuel feed tank. 2 represents a float therein. 3 represents a bell crank lever mounted on a suitable support 4 and connected at its upper end with a valve mechanism 5. In Figs. 1 and 2 this valve is a one-piece structure having two pointed ends a—b. 6 is a vent pipe which leads into the interior of the tank 1. 7 is an exhaust pipe which also opens into the interior of the tank 1 and which is suitably connected to the exhaust means E. The end b of the valve member 5 projects into the inner end of the exhaust pipe 7. One of these pipes, preferably the pipe 7, is adjustable, any suitable adjusting means being provided. In this instance, the adjusting means comprises a nut 8 threaded on the outer side of the pipe so that it may be moved to and fro. This nut 8 forms a combined washer and abutment shoulder against which a gland 9 may abut so that by means of the gland the nut 8 may be drawn tightly into place and

thereby hold the pipe 7 in its desired adjusted position as shown in Fig. 1. 10 is a supply pipe which leads from the supply tank T to the feed tank 1. 11 is an ordinary check valve therein. 12 is an outlet or feed pipe which conveys fuel to the carburetor or vaporizer C. It is preferable to mount an intermediate reservoir 14 in the path of feed and in this instance the pipe 12 projects into the bottom of said reservoir and a continuation of said pipe 12 leads from the bottom of said reservoir to the part C. 15 is a suitable back check valve. 16 is a vent for the reservoir 14. The valve member 5 when it closes the vent pipe 6 as shown in Fig. 1, opens the exhaust pipe 7, and, when it is moved into the position to choke the exhaust pipe 7 it opens the vent pipe 6. By making the ends of the valve member 5 tapered, it is obvious that when said valve member is moved to the left from the position shown in Fig. 1, it will gradually open the vent and gradually close the exhaust. I prefer to provide in the side of the valve at the end arranged to co-operate with the exhaust 7, a small groove d so that the valve will never completely close the exhaust.

Operation: When the parts stand as shown in Fig. 1, the vent 6 is fully closed, while the exhaust 7 is open to the interior of the tank. This will create a sufficient vacuum to raise fuel from the supply tank T through the pipe 10 from which it will flow into the feed tank 1. As the level rises, the float 2 will be lifted which will gradually shift the valve 5 from the right to the left, as viewed in Fig. 1. This will gradually open the vent and gradually close the exhaust. When the vent has been sufficiently opened, and the exhaust has been closed, the vacuum in the tank 1 will be lowered to a point where it will be insufficient to lift fuel from the supply tank T. It might be stated that during this filling operation the valve 15 in the feed pipe is closed so that fuel in the reservoir 14 may freely run to the carburetor C. As soon as the vacuum ceases, the fuel in the tank 1 will readily flow into the reservoir 14 and fill it to its intended level. It will be noted that the gas drawn through the exhaust pipe 7 is always charged more or less with the vapors of the fuel, since the pipe 7 is never put in direct communication with the atmosphere in the preferred construction.

Hence, the mixture in the manifold E will never be unduly adulterated.

- In Fig. 3, 10 represents the supply pipe as before. 7 represents the exhaust pipe and 6 5 represents the vent pipe. 1 represents the fuel feed tank, 2 represents the float. 3^a represents a walking beam mounted on a suitable support 4^a. The walking beam forms part of the valve mechanism which also includes 10 the pointed valve ends a' and b'. These valve ends project respectively into the exhaust and vent pipes and are so arranged that when the vent 6 is fully closed, the exhaust 7 will be fully open. As the float 2 15 rises the vent will be gradually opened and the exhaust will be gradually closed until air will flow in through the former at greater speed than it will be exhausted through the latter, whereupon the fuel in 20 the feed tank 1 may flow out through the feed pipe 12 by gravity.
- It is obvious that the various parts may be constructed in a variety of ways, my main purpose in the present invention being to provide 25 a valve mechanism which is controlled by the level of fuel in the feed tank and which will so change the effectiveness of the exhaust relatively to the effectiveness of the vent and vice versa, that when the level of 30 fuel is lowered to a certain point in the feed tank, fuel will be drawn in from a suitable supply source until the desired level is re-established whereupon the vent will be sufficiently opened to render the vacuum ineffective 35 for the purpose of drawing in more fuel until the level again lowers in the feed tank. Obviously the reservoir 14 or any equivalent means, may be associated with the tank shown in Fig. 3, if desired.
- 40 For adjustment either or both of the pipe ends 6-7 where they enter the tank 1 may be adjusted up and down relatively to the valve ends b'-a'. This adjustment may be effected in any desired way and is conventionally illustrated by the screw thread shown. Each of these pipe ends may have a lock nut thereon to hold the pipes in the desired positions of adjustment. The lock nuts are indicated at 17-17.
- 50 The valve mechanism in each of the modifications it will be observed has an unbalancing effect. That is to say, it allows the vacuum in the feed tank to increase to the effective point where it will draw in liquid 55 from the main supply tank and allows it to decrease to a point where the supply will cease running in and the contents of the feed tank may discharge by gravity. Obviously the means by which this is accomplished 60 may be modified in a great variety of ways and I have attempted to show only two forms herein. I apprehend also that ordinary adjusting means may be employed on any or all parts of the valve mechanism 65 for the purpose of securing the desired oper-

ation thereof, and I do not desire to limit myself to any specific form of adjusting means for that purpose.

What I claim is:

1. In an apparatus of the character described, a tank, a liquid supply pipe leading into the same, a vent pipe leading into the same, an exhaust pipe leading into the same and automatically controlled valve mechanism coöperating with the exhaust and 75 the vent pipes to vary the degree of vacuum in said tank by varying the area of the exhaust passage.

2. In an apparatus of the character described, a tank, a liquid supply pipe leading into the same, a vent pipe leading into the same, an exhaust pipe leading into the same and automatically controlled valve mechanism coöperating with the exhaust and the vent pipes to vary the degree of vacuum 85 in said tank by varying the area of the exhaust passage, said automatic means including a float movable by the variation of liquid level in said tank.

3. In an apparatus of the character described, a tank, a liquid supply pipe leading into the same, a vent pipe leading in the same, an exhaust pipe leading into the same and automatically controlled valve mechanism coöperating with the exhaust and the 95 vent pipes to vary the degree of vacuum in said tank by varying the area of the exhaust passage, and an auxiliary feed reservoir in communication with said tank and a check valve in the line of said communication.

4. In an apparatus of the character described, a tank, a liquid supply pipe leading into the same, a vent pipe leading into the same, an exhaust pipe leading into the same and automatically controlled valve mechanism coöperating with the exhaust and the vent pipes to vary the degree of vacuum in 105 said tank by varying the area of the exhaust passage, and an auxiliary feed reservoir in communication with said tank and a check valve in the line of said communication, 110 said reservoir having a vent.

5. In an apparatus of the character described, a tank, a liquid supply pipe leading into the same, a vent pipe leading into the same, an exhaust pipe leading into the same and automatically controlled valve mechanism coöperating with the exhaust and the vent pipes to vary the degree of vacuum in 115 said tank by varying the area of the exhaust passage, and a check valve in said supply pipe.

6. In an apparatus of the character described, a tank, a liquid supply pipe leading into the same, a vent pipe leading into the same, an exhaust pipe leading into the same and automatically controlled valve mechanism coöperating with the exhaust and the vent pipes to vary the degree of vacuum in 125 130

said tank by varying the area of the exhaust passage, said valve mechanism being adjustable.

7. In an apparatus of the character described, a tank, a liquid supply pipe leading into the same, a vent pipe leading into the same, an exhaust pipe leading into the same and automatically controlled valve mecha-

nism coöperating with the exhaust and the vent pipes to vary the degree of vacuum in said tank by varying the area of the exhaust passage, said valve mechanism including means for gradually closing the vent while simultaneously opening the exhaust and vice versa.

ROBERT C. MITCHELL.
